UNITED STATES PATENT OFFICE.

RICHARD D. CHANDLER, OF HYDEPARK, MASSACHUSETTS, ASSIGNOR TO CHANDLER SPECIALTY COMPANY, OF BOSTON, MASSACHUSETTS, A CORPORATION OF SOUTH DAKOTA.

DESIGN FOR A LAMP-SHADE.

SPECIFICATION forming part of Design No. 36,293, dated April 21, 1903.

Application filed May 19, 1902. Serial No. 108,110. Term of patent 8½ years.

To all whom it may concern:

Be it known that I, RICHARD D. CHANDLER, a citizen of the United States, residing at Hyde-park, in the county of Norfolk and State of Massachusetts, have invented and produced a new, original, and ornamental Design for Shades for Lamps, of which the following is a specification, reference being had to the accompanying drawing, forming part thereof.

o The drawing is a view in perspective of a shade for lamps, showing my new design.

As shown in the drawing, the leading or material feature of my design consists of a series of petal-shaped panels A A, whose exterior surfaces are convex, said panels being arranged as shown in the drawing and having a broad curved base, the sides being compound curves approaching each other in general direction and meeting at the top in a

curve slightly pointed. The upper portion of each panel A flares outwardly. The edges of the panels are bound with a narrow binding B, and the panels are so arranged to form the shade that the middle portions of their adjacent sides interlock.

Having described my invention, what I claim as new, and desire to secure by Letters Patent, is—

The ornamental design for a lamp-shade, as herein shown and described.

In testimony whereof I have signed my name to this specification in the presence of two subscribing witnesses.

RICHARD D. CHANDLER.
